UNITED STATES PATENT OFFICE.

EMERSON G. REED, OF WILKINSBURG, PENNSYLVANIA, ASSIGNOR TO WESTINGHOUSE ELECTRIC & MANUFACTURING COMPANY, A CORPORATION OF PENNSYLVANIA

SUPPORTING MEANS FOR ELECTRIC APPARATUS.

No. 854,309.

Specification of Letters Patent.

Patented May 21, 1907.

Application filed November 3, 1906. Serial No. 341,922.

To all whom it may concern:

Be it known that I, EMERSON G. REED, a citizen of the United States, and a resident of Wilkinsburg, in the county of Allegheny and State of Pennsylvania, have invented a new and useful Improvement in Supporting Means for Electric Apparatus, of which the following is a specification.

My invention relates to inclosed electric apparatus, and has special reference to means for rigidly supporting the cores and windings of alternating current transformers in suitable tanks or cases.

The object of my invention is to provide simple and durable means of the aforesaid class that may be readily adjusted to various sizes of transformers having inclosing tanks which may or may not correspond exactly to the size of the transformer.

Commercial alternating current transformers are almost universally provided with inclosing tanks or casings of some kind and, for transformers of the smaller sizes, cast iron tanks are often employed. The transformers themselves, apart from the tanks, comprise relatively heavy core members upon which coils are mounted. Consequently, they must be rigidly supported in the tanks in which they are located in order to avoid injury to the conducting leads and to the exposed portions of the windings.

In the prior art, projecting ears were often formed integral with, or were attached to, the interior walls of the casing and corresponding ears projected laterally from the core structure and were readily secured to the casing by passing clamping bolts through holes in the projections. The limited service to which a single casing can be applied is the principal disadvantage in an arrangement of this kind, in consequence of which a great number of patterns and tools are required for molding and finishing casings which are adapted for the various transformer sizes ordinarily carried in stock by manufacturers of electrical apparatus. This objection is obviated by the device of my invention, which may be adjusted with facility and ease to support, in a single casing, transformers that differ materially in size and style.

Figure 1 of the accompanying drawing is a view, partially in elevation and partially in section, of a tank having a core type trans-

former supported therein by means of the improved device of my invention. Fig. 2 is a plan view of a portion of the transformer and the support shown in Fig. 1.

Referring to the drawings, the transformer illustrated comprises a laminated core structure 1, upon which coils 2 are mounted, and an inclosing tank or casing 3. The laminated core structure 1 is bound together at the top and bottom by end plates 4, 5, 6, and 7, the upper plates being provided with projecting ears 8 and 9 and the lower plates 6 and 7 being provided with projections 10 and 11 which form a standard or base for the assembled transformer.

The casing 3 may be of any suitable structure, a well known form being illustrated which comprises a cast iron tank having corrugated walls to increase the external radiating surface and a ledge or shelf 12 in which suitable bushings 13 for the transformer leads, are supported. Downwardly extending, wedge-shaped projections 14 having longitudinal slots 15 cut in their centers are provided on two opposite side walls of the casing substantially at the level of the top of the transformer core. A tie-bolt 16 is passed through holes in the projecting ears 8 and 9 of the clamping plates 4 and 5 and is held in position relative thereto by nuts 17 and lock washers 18. The length of the bolt is such that when it is in position, the transformer may readily be lowered into the casing, the ends of the bolt projecting into the slots 15 of the wedge-shaped projections. Washers 19 having beveled surfaces adapted to engage the wedge-shaped projections 14, are loosely fitted upon the ends of the tie-bolt 16 and adjusting nuts 20 are adapted to force the washers against the projections when the transformer is in position. The inner surfaces of the wedge-shaped projections 14 are so arranged, with the points of the wedges downward, that, as the adjusting nuts 20 are forced against the washers 19, the transformer coil is forced against the bottom of the transformer casing and is held rigidly in position.

The form of the supporting projections and the engaging washers may be varied, the other modifications may obviously be effected without departing from the spirit of my invention.

The simplicity and security of the clamping device, as hereinbefore described, makes it specially desirable and it is practically impossible for a transformer, once properly fastened in its case, to work loose.

Although I have illustrated a core type transformer, the means for clamping the transformer to the casing is obviously not confined to any specific structure and I desire that only such limitations be imposed as are indicated in the appended claims.

I claim as my invention:

1. The combination with a transformer casing, of adjustable means for supporting a transformer therein.

2. The combination with a transformer comprising a laminated magnetizable core, a supporting frame therefor, and a plurality of coils, of an inclosing casing, and adjustable means for supporting the transformer in the casing.

3. The combination with a transformer and a casing therefor, of adjustable means comprising a tie-bolt attached to the transformer and end blocks or washers which are forced against the inside walls of the casing for supporting the transformer in the casing.

4. The combination with a transformer comprising a laminated magnetizable core, a supporting frame therefor, and a plurality of coils, of an inclosing casing, and adjustable means comprising a tie-bolt that is attached to the transformer core and end blocks or

washers which are forced against the inside walls of the casing for supporting the transformer therein.

5. The combination with a transformer and a casing having wedge-shaped projections on its inside walls, of adjustable means comprising a tie-bolt that is attached to the transformer core, and beveled end blocks or washers which are forced against the wedge-shaped projections for locking the transformer in the casing.

6. The combination with a transformer comprising a laminated magnetizable core, a binding end frame therefor, ears projecting outwardly from the frame, and a plurality of coils mounted on the core, of an inclosing casing for the transformer having wedge-shaped inward projections and means comprising a tie-bolt that extends through suitable holes in said projecting ears, binding nuts therefor, beveled washers fitted loosely upon the ends of the tie-bolt, the outer surfaces of which are adapted to engage the wedge-shaped projections on the casing, and adjusting nuts which are adapted to force said washers against said projections.

In testimony whereof, I have hereunto subscribed my name this 31st day of October, 1906.

EMERSON G. REED.
